UNITED STATES PATENT OFFICE.

MERRICK F. WILSON, OF CHICAGO, ASSIGNOR OF ONE-HALF TO CHARLES R. STEELE AND V. CLARENCE PRICE, BOTH OF WAUKEGAN, ILLINOIS.

BOX-FORMER.

SPECIFICATION forming part of Letters Patent No. 350,961, dated October 19, 1886.

Application filed May 15, 1885. Serial No. 165,646. (No model.)

To all whom it may concern:

Be it known that I, MERRICK F. WILSON, a citizen of the United States, and residing at Chicago, in the county of Cook and State of Illinois, have invented certain new and useful improvements in Box-Formers, which are fully set forth in the following specification, reference being had to the accompanying drawings, in which—

10 Figure 1 is an elevation, partly in section, of a former embodying my invention; and Fig. 2, a plan view of the same.

Like letters refer to like parts in both the figures of the drawings.

15 My invention relates to box-formers, its object being to facilitate the operation of removing the completed box or box-top from the former; and to that end it consists in certain novel features, which I will now proceed to describe, and will then particularly point out in the claims.

In the drawings I have shown my improvement as applied to a box-former of the description set forth in an application for Letters 25 Patent filed by me July 14, 1884, Serial No. 137,715, in which A represents the standard, B the stem, and C the clamp for securing the stem to the standard.

D represents the revolvable head; D', the top 30 plate thereof; E, the base-plate adjustably attached thereto; F, the adjustable jaws mounted to said base-plate, and f' the screws which secure the said adjustable jaws together. These parts are all constructed substantially as in 35 my application hereinbefore referred to, reference to which is made for a further description of the same.

G indicates the stripper, which consists of a rod passing through the stem B, which is made 40 hollow to receive the same, the said rod being of greater length than the stem, and being provided at one end with a head, G', of suitable size and form, and at the other end with a foot-piece, G². The upper end of the said rod is 45 squared, as shown at g, for a portion of its length adjacent to the head G', the said squared portion passing through a groove, g', of corresponding width in the base-plate E.

In the construction of boxes in which a 50 former is employed upon which the box is

wholly or partially constructed the operation of removing the box when completed from the former is attended with some little difficulty, owing to the impossibility of properly grasping the box without compressing it against the former. This difficulty is entirely overcome by the use of my improved stripper, in the operation of which, by pressing against the foot-piece G², the head G' will be brought against the bottom of the box with a degree 55 of force corresponding to that applied to the other end of the stripper, and will remove the box readily without the application of the hand thereto in a simple and effective manner. In case the box should happen to stick 60 on account of the closeness of its fit upon the former, or of the presence of any glue between it and the former, the force which may be applied to it by the use of my improved stripper will be sufficient to readily remove the same. 65

In the application of my stripper to the description of box-former shown in the drawings it will be seen that the squared portion g of the rod or stem of the stripper, being in contact with the walls of the slot g', will rotate 70 with the revolvable head and parts attached thereto, so as to keep the head G' in proper relative position to the jaws F. This construction is, however, only necessary when a head rectangular in form is employed, as is 75 the case in the construction shown in the drawings, and any well-known equivalent device may be employed—such as a spline-and-groove connection between the rod and base-plate, or pins passing from the head G' through the 80 plate and revolvable head. When the head is circular in form, any connection to cause it to rotate with the former proper may be dispensed with.

It will be observed that the head G and foot-piece G² form stops which limit the movement of the stripper and prevent its becoming detached or moving too far in either direction. A spring may be employed to retract the stripper, so as to bring it to its normal position, with the head G' at its maximum distance 95 from the bottom of the box when the same is in place.

The head G' may be constructed of a size equal in its dimensions to the space within 100

the jaws F when they are adjusted to that position which brings them most closely together.

It is obvious that although I have shown my improvement as applied to a particular description of box-former of my own invention, it is equally applicable to any other approved kind of box-former.

It is also obvious that various mechanical modifications may be made in the details of construction without departing from the principle of my invention, and I therefore do not wish to be understood as limiting myself strictly to the precise details of construction hereinbefore described, and shown in the drawings.

I am aware of Letters Patent No. 126,378, granted May 7, 1872, to George R. Clarke, and I do not wish to be understood as claiming anything set forth in said Letters Patent.

Having thus described my invention, what I claim as new, and desire to secure by Letters Patent, is—

1. The combination, with a box-former consisting of a revoluble head upon which the former proper is mounted, and a stem upon 25 which the revoluble head is mounted, of the stripper extending through the stem and capable of rotation therein and connected to the former proper, so as to rotate therewith, substantially as and for the purposes specified. 30

2. The combination, with the stem B, the revoluble head D, and base-plate E, adjustably mounted to said head, and provided with slot g', of the stripper G, having head G' attached to a round rod extending through the 35 said stem, and having its upper portion squared at g', to fit between the walls of the slot g', substantially as and for the purposes specified.

MERRICK F. WILSON.
